CURTAIN AND BLANKET STRETCHER

Application filed December 27, 1929. Serial No. 416,814.

This invention relates to an improved adjustable portable stretcher on which curtains and blankets may be stretched while drying after being washed or cleaned.

An object of the present invention is to provide an efficient stretcher of the above kind on which the articles to be stretched may be arranged with ease and facility, and which may be readily adjusted to accord with the sizes of the articles to be stretched thereon.

Another object is to provide a stretcher which is simple and durable in construction, economical to manufacture, and otherwise well adapted to meet with all of the requirements for successful commercial use.

A further object is to provide a stretcher embodying horizontal and vertical adjustable stretcher bars, and improved means for releasably holding said stretcher bars in any desired position of adjustment.

Other objects will appear as the nature of the invention is better understood, and the same consists in the novel form, combination and arrangement of parts hereinafter more fully described, shown in the accompanying drawings, and claimed.

In the drawings:

Figure 1 is a side elevation, partly broken away and in section, of a stretcher embodying the present invention.

Figure 2 is an enlarged fragmentary vertical section, showing details of an upper corner portion of the stretcher frame and adjacent parts.

Figure 3 is a top plan view of the construction shown in Figure 2.

Figure 4 is an enlarged vertical transverse section on line 4-4 of Figure 1.

Figure 5 is a fragmentary vertical longitudinal section on line 5-5 of Figure 4.

Figure 6 is an enlarged horizontal section on line 6-6 of Figure 1.

Figure 7 is a fragmentary vertical longitudinal section on line 7-7 of Figure 6; and

Figure 8 is an enlarged vertical section on line 8-8 of Figure 1.

The present stretcher includes a rectangular frame composed of a horizontal top mem-

ber 5, a horizontal bottom member 6, and vertical end members 7 and 8 having their adjacent ends rigidly connected at three corners of the frame by means of divided angle braces 9, 10 and 11 bolted in place as at 12. Rigidly mounted in the upper portion of the stretcher frame below the top frame member 5 is an intermediate horizontal stationary stretcher bar 13 which carries a horizontal scale bar 14 suitably graduated in inches or the like. A similar vertical scale bar 15 is carried by the end frame member 8 between the intermediate stretcher bar 13 and the bottom frame member 6. On the outside of the remaining upper corner of the stretcher frame is fitted the angle base 16 of a divided hanger casting 17. The sections of the casting 17 are bolted together as at 18, and the vertical leg of the base 16 is bolted to the end frame member 7 and the vertical leg of a corner brace 19 as at 20. The brace 19 is fitted on the inside of the adjacent upper corner of the stretcher frame and is additionally bolted at 21 to the end frame member 7, the brace 19 also having a bottom foot 22 bolted at 23 to the adjacent end of the stationary intermediate stretcher bar 13. The other end of the bar 13 is attached to the end frame member 8 by means of a divided angle brace 24.

The frame members 5, 6, 7 and 8 and the fixed stretcher bar 13 are in the nature of sheet metal tubes of rectangular cross-section and centrally longitudinally slotted respectively at their inner and upper sides, the portions of the tubes at opposite sides of the slots being inturned as at 25. Rigid with the corner brace 19 are lugs 26 which project into the slots of the frame members 5 and 7 to facilitate firm fastening of the latter and proper positioning of said brace.

Movable vertically between the fixed stretcher bar 13 and the bottom frame member 6 is a horizontal adjustable lower stretcher bar composed of a pair of spaced members 27 rigidly connected by brackets 28 and having outer inturned longitudinal edges, forming guides or holders for strips 29 of card clothing, the pins of which are adapted to impale the articles to be stretched.

Attached to opposite sides of the top and end frame members 5 and 7 and the fixed bar 13 are similar holders 27a which carry similar strips 29a of card clothing, for a like purpose. Similarly movable horizontally between the end frame members 7 and 8 is a vertical adjustable stretcher bar composed of a pair of spaced members 27b rigidly connected by brackets 28b and having outer inverted longitudinal edges, forming holders for further strips 29b of card clothing.

Rigidly attached to the opposite ends of the stretcher bar members 27 are brackets 30, and slidably in these brackets between said members are the horizontal stems 31 of brake shoes 32 retracted by springs 33 and adapted to be manually projected into frictional engagement with the inner faces of the adjacent frame members 7 and 8. The brake shoes 32 have projecting lugs 34 which slidably engage in the slots in the inner sides of the frame members 7 and 8 to guide the adjustable horizontal lower stretcher bar in its vertical movements. The inner ends of the brake shoe stems 31 are connected to the downwardly offset ends of a horizontal brake operating bar 35 by means of links 36, and pivoted to the brackets 30 are further links 37 whose lower ends are pivoted to the adjacent ends of the stems 31 and links 36. The arrangement is such that when the bar 35 is lifted, the brake shoes 32 are released by the springs 33 from the frame members 7 and 8, thereby permitting the lower horizontal stretcher bar to be vertically adjusted. The bar 35 is then pressed downwardly to project the brake shoes 32 and to move the ends of the bar 35 and the adjacent ends of the links 36 below the plane of the stems 31, thereby providing a past-center effect whereby the brake shoes are held in frictional contact with the frame members 7 and 8 to hold the lower horizontal stretcher bar in adjusted position.

In order to counter-balance the lower horizontal stretcher bar, the opposite ends thereof are connected by flexible members 38, 39, 40 and 41 to weights 42 and 43. The casting 17 and braces 9 embody pairs of upstanding plates 44 and 45 between which are respectively journaled pulleys 46 and 47. The flexible member 38 is attached at one end to the bracket 30 at one end of the adjustable lower horizontal stretcher bar and passes upwardly and outwardly over aligned ones of the pulleys 46, and then downwardly at the adjacent end of the frame where its other end is attached to the weight 42 which is movable in a vertical guide tube 48 mounted on said adjacent end of the frame. The flexible member 41 is attached to the other bracket 30 and passes over aligned ones of the pulleys 47, and then downwardly at the adjacent other end of the frame where it is attached to the weight 43 which is movable in a further ver-

tical guide tube 49 mounted on said adjacent other end of the frame. The flexible member 39 is attached to the bracket 30 at one end of the frame and passes over certain of the pulleys 46 and 47 to the opposite end of the frame where it is attached to the weight 43. In a like manner, the flexible member 40 is attached to the other bracket 30 and passes over other of the pulleys 46 and 47 to opposite end of the frame where it is attached to the weight 42. The guide tubes 48 and 49 are supported at their lower ends by brackets 50 attached to the end frame members 7 and 8, and the upper ends of these guide tubes are held between complementary jaws 51 integral with the sections of the casting 17 and the upper corner brace 9.

The top connecting bracket 28b for the adjustable vertical stretcher bar members 27b embodies a casting provided with a top plate member 52 provided with lugs 53 which slidably project into the bottom slot of the top frame member 5 as shown in Figure 5. A hanger 54 is adjustably connected with the plate 52 by means of a threaded stem 55 passing through said plate 52 and having nuts 56 threaded on its lower end. The hanger 54 has spaced pairs of rollers 57 which track on the bottom wall of the top frame member 5 at opposite sides of its longitudinal slot. A similar lug carrying bracket plate and hanger slidably connect the lower ends of the stretcher bar members 27b with the bottom frame member 6 as generally indicated at 58. The top bracket 28b further has an elongated bottom bar 59 braced as at 60 and carrying three roller carriages 61, 62, and 63 whose rollers track on the top wall of the fixed horizontal stretcher bar 13 at opposite sides of its longitudinal slot. The carriages 61, 62, and 63 have threaded stems 64 which pass freely through the bar 59 and have nuts 65 threaded on their upper ends so that the carriages may be adjusted to cause the rollers thereof to properly engage the top wall of the bar 13. These carriages are arranged in tandem relation, the end ones thereof acting to maintain the bar members 27b in a vertical position. The underside of the intermediate portion of the bar 59 is faced with a strip of friction material 66, and pivoted to a nut on the stem 64 of the intermediate carriage 62 is a cam lever 67. By swinging the lever 67 downwardly to the position of Figure 5, its cam presses the faced intermediate portion of the bar 59 into frictional engagement with the top of the bar 13, thus holding the stretcher bar members 27b in any position to which they are adjusted. By lifting the lever 67, the intermediate brake portion of the bar 59 is released from the bar 13 so as to permit free horizontal adjustment of said members 27b. In use, small curtains and the like can be stretched by raising the adjustable lower

horizontal stretcher bar 27, 27 to the required position and applying the brake shoes 32 to lock said bar in position, measurements being taken from the fixed bar 13 on the scale 15. This setting is done to correspond to the width of the curtain. The adjustable vertical stretcher bar 27b, 27b is then adjusted the desired distance from the end frame bar 7 to correspond to the length of the curtain, measurements being taken at this time on the scale 14. This sets the stretcher for simultaneously stretching curtains of similar size on both sides of the stretcher. Large curtains or single blankets can be accommodated by setting the horizontal bar 27, 27 the proper distance from the top frame bar 5 and by setting the vertical bar 27b, 27b the proper distance from the end frame bar 7. Double blankets or the like can be stretched by passing them around the guide tube 48 and the end frame bar 7, the ends of the blanket being attached to opposite sides of the vertical bar 27b, 27b the upper edge of the blanket being attached to opposite sides of either the top frame bar or the fixed intermediate bar 13, and the lower edge of the blanket being attached to opposite sides of the lower horizontal bar 27, 27.

One or both of the lower corner braces 10 and 11 may be provided with a supporting roller or rollers 68 to facilitate movement of the stretcher over the floor or ground from one place to another, if desired.

What we claim is:

35 1. In a curtain and blanket stretcher, a rigid rectangular frame composed of top and bottom horizontal members and vertical end members, roller-supporting castings joining the adjacent ends of the end and top frame members at the upper corners of the latter, a guide tube mounted at each end of the frame, means carried by each casting for securing the adjacent guide tube in a vertical position at the outer side of the adjacent end frame member, a horizontal lower vertically adjustable stretcher bar movably mounted in the frame and slidably engaged with the end frame members, and counter-balancing means for said lower horizontal vertically adjustable stretcher bar including weights vertically movable in the guide tubes and flexible members connected to the ends of said lower horizontal stretcher bar and passing upwardly over the rollers of said castings and attached to said weights.

2. In a curtain and blanket stretcher, a rigid rectangular frame composed of top and bottom horizontal members and vertical end members, roller-supporting castings joining the adjacent ends of the end and top frame members at the upper corners of the latter, a guide tube mounted at each end of the frame, means carried by each casting for securing the adjacent guide tube in a vertical position at the outer side of the adjacent end

frame member, a horizontal lower vertically adjustable stretcher bar movably mounted in the frame and slidably engaged with the end frame members, and counter-balancing means for said lower horizontal vertically adjustable stretcher bar including weights vertically movable in the guide tubes and flexible members connected to the ends of said lower horizontal stretcher bar and passing upwardly over the rollers of said castings and attached to said weights, one flexible member being attached to each end of the lower horizontal stretcher bar and to the weight at the adjacent end of the frame, another of the flexible members being connected to each end of the horizontal lower stretcher bar and connected to the weight at the opposite end of the frame. 70 75 80

3. In a curtain or blanket stretcher, a rigid rectangular frame composed of horizontal top and bottom frame members and vertical end frame members, each of said frame members embodying a hollow tube longitudinally slotted at the inner side thereof, a fixed horizontal intermediate stretcher bar mounted in the upper portion of the frame below the top frame member and embodying a hollow tube longitudinally slotted at the upper side thereof, a vertical horizontally adjustable stretcher bar mounted in the frame and slidably engaged at its ends in the slots of the top and bottom frame members, carriages carried by the ends of said vertical stretcher bar and having wheels tracking on the inside of the top and bottom frame members at opposite sides of the slots thereof, and a plurality of further carriages attached to the vertical stretcher bar and tracking on the lower surface of the top wall of said fixed intermediate stretcher bar at opposite sides of the slot thereof. 90 95 100 105

4. In a curtain or blanket stretcher, a rigid rectangular frame composed of horizontal top and bottom frame members and vertical end frame members, each of said frame members embodying a hollow tube longitudinally slotted at the inner side thereof, a fixed horizontal intermediate stretcher bar mounted in the upper portion of the frame below the top frame member and embodying a hollow tube longitudinally slotted at the upper side thereof, a vertical horizontally adjustable stretcher bar mounted in the frame and slidably engaged at its ends in the slots of the top and bottom frame members, carriages carried by the ends of said vertical stretcher bar and having wheels tracking on the inside of the top and bottom frame members at opposite sides of the slots thereof, and a plurality of further carriages attached to the vertical stretcher bar and tracking on the lower surface of the top wall of said fixed intermediate stretcher bar at opposite sides of the slot thereof, a bracket carried by the vertical stretcher bar and having an elongated base 115 120 125 130

- bar to which the last-named carriages are attached, the intermediate portion of said base bar having a bottom facing of frictional material, and manually operable means for pressing said intermediate portion of the base bar into frictional engagement with the upper surface of said fixed stationary stretcher bar for releasably holding the vertical adjustable stretcher bar in any position of adjustment.
15. In a curtain or blanket stretcher, a rigid rectangular frame composed of horizontal top and bottom frame members and vertical end frame members, each of said frame members embodying a hollow tube longitudinally slotted at the inner side thereof, a fixed horizontal intermediate stretcher bar mounted in the upper portion of the frame below the top frame member and embodying a hollow tube longitudinally slotted at the upper side thereof, a vertical horizontally adjustable stretcher bar mounted in the frame and slidably engaged at its ends in the slots of the top and bottom frame members, carriages
- 20 carried by the ends of said vertical stretcher bar and having wheels tracking on the inside of the top and bottom frame members at opposite sides of the slots thereof, and a plurality of further carriages attached to the vertical stretcher bar and tracking on the lower surface of the top wall of said fixed intermediate stretcher bar at opposite sides of the slot thereof, and means for adjusting said carriages into intimate rolling contact
- 25 with the walls of said top, intermediate and bottom frame members.

In testimony whereof we affix our signatures.
